DROPPER

Louis W. Schaaff, Jackson Heights, N. Y., assignor
to Waldes Koh-I-Noor, Inc., Long Island City,
N. Y., a corporation of New York

Application February 16, 1942, Serial No. 431,169

7 Claims. (Cl. 221—148)

This invention relates to improvements in droppers of the type commonly referred to as medicine droppers, although it will be understood that droppers in accordance with the present invention are capable of general usage in measuring and dispensing liquids other than medicines.

Droppers as usually constructed employ an open-ended glass tube formed with a restriction at one end and carrying a rubber bulb at the other which is manipulated to both fill the dropper and to expel the liquid therefrom in the form of drops. While this form of dropper has enjoyed wide usage, it is nevertheless open to objection, notably the difficulty in cleaning, the requirement that a nice degree of pressure be exerted on the bulb in dispensing drops therefrom, and the deleterious effect that both time and chemicals have on the rubber bulb used therewith. Moreover, shortages in essential raw materials such as rubber give indication that rubber bulbs for droppers will not be readily available, and make apparent the necessity of developing a substitute for the rubber bulb or of providing a functionally effective dropper which does away entirely with the rubber bulb.

The present invention contemplates and has for its principal objects the provision of a novel and improved dropper which is effective in operation, which is so constructed that the requirement of a rubber bulb for operating the same is dispensed with entirely, and which instead may be manufactured complete from readily available materials; the provision of a dropper which accurately forms and measures each drop regardless of the force or pressure applied in manipulation; the provision of a dropper which may be readily taken apart and cleaned; and the provision of a dropper which is of rugged and substantially non-breakable construction, which can be inexpensively fabricated and assembled in quantity, and which is unaffected by age and the chemicals with which it is used.

Other objects will be in part obvious and in part hereinafter pointed out in connection with the following analysis of this invention wherein is illustrated an embodiment of the invention in detail.

In the drawing—

Fig. 1 is a front elevation of the improved dropper of the present invention;

Fig. 2 is a rear elevation of the dropper illustrated in Fig. 1;

Fig. 3 is a section along line 3—3 of Fig. 1;

Fig. 4 is a section along line 4—4 of Fig. 1.

In the drawing, wherein like characters designate like parts throughout the several views, the improved dropper is shown as constituted by two elongated half-sections 10 and 12 which are hingedly related by a hinge pin 14, of which the section 10 will be referred to as the front section and the section 12 as the rear section. Each section is provided with a flat, outwardly convexed handle or grip portion, the grip portion 12a of the under section terminating in a forwardly extending tongue 12b of depth corresponding to the thickness of the end of the upper grip portion 10a of the front section. The upper terminal edge 10b of the front section is normally spaced slightly from the under face of the tongue, but when finger pressure is exerted on the grip portions the handle portion 10a elongates slightly whereupon its top edge engages against the tongue which thereupon acts as a stop and limits the degree of finger pressure which can be exerted.

Somewhat below its grip portion the rear section is provided with forwardly extending hinge ears 12c spaced to receive a mating ear 10c formed on the front section and extending rearwardly thereof. The hinge pin 14 projects through said ears and thus hingedly connects the sections.

Below the hinge ear each section is formed with an elongated semi-cylindrical portion, the elongated portion 12d of the rear section opposing the like portion 10d of the front section. Thus the elongated portions 10d, 12d complement each other to provide an elongated tubular reservoir of small diameter for the liquid to be dispensed which will hereinafter be termed the reservoir portion.

The lower end of each semi-cylindrical portion connects with a semi-spherical portion of radius substantially greater than the radius of the semi-cylindrical portions. Like the latter portions, the semi-spherical portions designated 10e and 12e are oppositely disposed as shown and thus combine to provide a hollow sphere constituting the lower end of the reservoir and functioning as the drop regulating portion of the device as will hereinafter appear.

Carried at the lower end of the semi-spherical portion 12e of the rear section is a downwardly extending discharge spout 12f which has relatively short length and is preferably semi-circular in section. The semi-spherical portion 10e of the front section carries a downwardly extending tongue 10g which as shown may extend at an angle of approximately 45° to the ver-

tical and has a contour such that it fits in the spout 12f and functions as a valve normally closing communication between the spherical drop regulating portion and the discharge spout or nozzle.

Preferably the sections are each fabricated complete from any approved plastic material which is readily available and which is moldable or capable of being worked in a die. Transparent or glass-like plastic materials are entirely adaptable for this use and, by reason of the transparency thereof, the use of such materials is recommended. Alternatively, the sections can be stamped or die-formed from one of the available metals, preferably a metal of a springy or flexible nature, the metal finish of which may be retained; or the metal sections may, either prior to or after assembly, be enamelled and thereupon baked or heat-treated. In either case the selected material should be such that the sections are flexible to the extent that when assembled and finger pressure is applied to one or both of the handle grip portions thereof, the spout and valve end of the sections have relative separating movement as indicated in dotted lines in Fig. 3 and that release of such finger pressure causes the sections to close in automatic manner. To add to the flexibility of the grip portions of the device the same are preferably provided with punched openings, of which the opening 10h of the front section may be of smaller diameter than the opening 12h of the rear section. This difference in dimensioning of the openings is also useful in enabling the user to distinguish between the front and rear of the dropper.

In use, the dropper is immersed in the liquid and, being open at its upper end, the liquid rises to the level of the liquid in the container from which it is taken. When withdrawn from the container the liquid is held by capillary attraction in the reservoir and dropper regulating portions of the device. To measure and dispense a drop, slight finger pressure is exerted on the handle portion thereof, causing the spout and valve ends of the sections to open sufficiently that the pressure of the column of the liquid in the reservoir portion causes enough liquid as will form a drop to escape under the valve and to flow down to the extreme end of the spout portion. Release of finger pressure on the grip portion causes the valve to again seat in the spout portion, thus to cut off the drop from the liquid column, whereupon the so-formed drop falls from the end of the spout portion under its own weight. Repeat operations as aforesaid may be carried on, each resulting in the formation and dispensing of a drop, until the liquid column is exhausted.

In the aforesaid operation, the spherical drop regulating portion constituted by the spherical half sections 10e, 12e serves not only in holding by capillary action a portion of the liquid column, but, by reason of its relatively great volume which is substantially larger than that of a drop of liquid, permits the drop to form and release itself from the liquid column when the equilibrium between the capillary holding action and the pressure of the liquid column is disturbed as by opening the valve 10g. Upon release of a drop from the liquid contained in the spherical portion, a very small quantity of the liquid remains therein, but upon closing the valve the liquid column lowers into the spherical portion the amount of the released drop.

By suitable calibration, the reservoir portion of the dropper can be preformed to hold a predetermined volume of liquid corresponding to a certain number of drops thereof. By molding the sections from one of the suggested plastic materials, extreme accuracy of liquid volume is obtained. To indicate the capacity of the reservoir in terms of drops contained therein, suitable markings indicated in Fig. 1 may be applied to the outer surface of one or both sections, preferably the front section 10. By fabricating the section from transparent plastic, the quantity of liquid held in the liquid column can be determined visually by reference to such markings.

Manipulation of the dropper as aforesaid results in the formation of drops which are equal in size and volume, account being taken of the viscosity of the liquid being dispensed and its specific gravity. It will also be self-evident that a dropper in accordance with the present invention provides greater uniformity of drop and greater accuracy as to the amount of liquid dispensed than droppers operated by a rubber bulb filled with air because in the latter case the size of the drop and the number of drops is a function of the pressure exerted on the bulb. With a dropper of the present invention, the drop forms irrespective of the degree of pressure exerted by the user, there being no provision for increasing this pressure or for accelerating the formation of the drops as by increased pressure.

From the foregoing analysis of the invention, it will be seen that a functionally effective dropper eliminating the requirement of a rubber bulb is provided. Such a dropper may readily be taken apart and cleaned, is unbreakable, and, in view of its simplicity of construction, lends itself admirably to economic, accurate production.

As many changes could be made in carrying out the above constructions without departing from the scope of the invention, it is intended that all matter contained in the above description or shown in the accompanying drawing shall be interpreted as illustrative and not in a limiting sense.

I claim:

1. A liquid dropper of the class described comprising two elongated half-sections cooperatively related to form a small diameter, generally tubular reservoir adapted to hold by capillary attraction a column of the liquid to be dispensed, a handle portion at one end of the reservoir, normally closed discharge means at the other end of the reservoir, and means whereby pressure exerted on the handle portion effects operation of said discharge means to release and discharge a single drop of the liquid contained in the reservoir.

2. A liquid dropper of the class described comprising two elongated half-sections cooperatively related to form a small diameter, generally tubular reservoir adapted to hold by capillary attraction a column of the liquid to be dispensed, a handle portion at one end of the reservoir, normally closed discharge means at the other end of the reservoir, said discharge means including a discharge spout on one section and a valve on the other section normally cutting off communication between said reservoir and the spout, and means whereby pressure exerted on the handle portion effects movement of the valve to open communication between the reservoir and the spout.

3. A liquid dropper of the class described comprising two elongated half-sections and means

hingedly securing the sections, said sections being shaped to provide a liquid reservoir including an elongated, small diameter tubular portion and connected to the lower end thereof, a hollow spherical drop-forming portion, a handle extending above the tubular portion, and a normally closed discharge means extending below the spherical portion.

4. A liquid dropper of the class described comprising two elongated half-sections, said sections cooperating to form a reservoir for liquid including an elongated tubular portion and connected to the lower end thereof, a hollow spherical drop-forming portion, a handle portion extending above the tubular portion, and a normally closed discharge means extending below the spherical portion, the said discharge means including a discharge spout on one section and a valve on the other section, normally cutting off communication between the spherical portion and the spout, and means whereby pressure exerted on the handle portion effects movement of the valve to open communication between the spherical portion and the spout.

5. A liquid dropper of the class described comprising two elongated half-sections, each including a handle portion, an elongated semi-cylindrical portion, a semi-spherical portion into which the lower end of the semi-cylindrical portion opens, one section having a downwardly extending discharge spout into which its semi-spherical portion opens, the other section having a tongue-like valve portion extending downward-

ly from its semi-spherical portion and normally closing off communication between the semi-spherical portion and the spout of the other section, and means pivoting said sections together whereby said semi-cylindrical and semi-spherical portions complement each other to form a liquid reservoir and whereby pressure applied to the handle portions operates to effect communication between the spherical portion and the spout.

6. A liquid dropper of the class described comprising two elongated half-sections which together form a small diameter tubular reservoir adapted to hold by capillary attraction a column of liquid to be dispensed, a handle portion at one end of the reservoir, normally closed discharge means at the other end of the reservoir, means whereby pressure exerted on the handle portion effects operation of said discharge means to release and discharge a single drop of the liquid contained in the reservoir, one of said sections carrying indicia representative of the drop capacity of the reservoir.

7. A liquid dropper of the class described comprising two elongated half sections which together form a tube of small diameter adapted to hold by capillary attraction a column of the liquid to be dispensed, said sections being provided at their one ends with connecting and operating means and at their opposite ends with portions complementing each other to form a normally closed discharge nozzle communicating with said tube.
